UNITED STATES PATENT OFFICE.

MAURICE LACHMAN, OF NEW YORK, N. Y.

POLE.

Specification of Letters Patent. Patented Apr. 18, 1916.

1,179,533.

Application filed April 20, 1910. Serial No. 556,547.

To all whom it may concern:

Be it known that I, MAURICE LACHMAN, a citizen of the United States, and a resident of the city of New York, county of 5 New York, and State of New York, have invented certain new and useful Improvements in Poles, of which the following is a specification.

This invention has particular reference to 10 poles such as are employed, for example, to carry insulators and conducting wires employed in electrical systems of lighting, telegraphy, telephony, and transportation, and it aims to provide for this and other 15 useful purposes a pole which can be inexpensively produced, is of maximum durability, and light in weight. This purpose is well secured by the constructions illustrated in the accompanying drawings to exemplify 20 what is at present regarded as very desirable forms of the invention, but to the details of which the invention, in its broader aspects, is not restricted.

In said drawings: Figure 1 is a side elevation of a pole embodying my improvements. Fig. 2 is a similar view of the pole, viewed from the side at right angles to that from which Fig. 1 is seen. Fig. 3 is a cross section on a larger scale, embodying a form in 25 which the elements are joined by "spot welding" the same together, showing the elements assembled before welding. Fig. 4 is a cross sectional view, on a smaller scale than Fig. 3, showing the appearance of the 30 elements after they have been welded. Fig. 5 is a view similar to Fig. 3 showing the elements formed for rib welding and assembled. Fig. 6 is a view of a vertical member formed with a ridge or rib for ridge welding. Fig. 7 is a view of a transverse member also formed with a rib. Fig. 8 is a view of the junction of such members. Fig. 9 is a 35 view similar to Fig. 4 of the pole when formed of members rib-welded together. Fig. 10 is a plan view, showing the pole 40 provided with lateral arms.

Similar characters of reference denote corresponding parts in the several views.

The pole herein illustrated contains vertical main supporting members A, shown as 45 flanged bars connected and braced by flat lattice members B. The lattice members are welded to the flat faces of the vertical bars to form a substantially integral structure, which is light and strong. The lattice members B preferably extend diagonally and in

such relation to each other that they will be welded to a vertical bar in substantially the same horizontal plane. These form some of the important features of the invention, 60 others of which will hereinafter appear.

There are preferably four of the vertical flanged bars A employed, disposed at the respective corners of the pole, here shown as approximately square in cross section, but it 65 will be understood that the pole may be of any other shape, as triangular, hexagonal, octagonal, or circular, for example. Each bar is preferably of L-shape in cross section, though other suitable shapes of flanged 70 bars may be employed. While the bars A are referred to as being vertical, they are preferably, in practice, somewhat inclined, as shown, so that the pole will be of less diameter at the top than at its base. 75

The lattice members B are preferably composed of a series of individual or separate metallic strips 15, disposed diagonally and in a zigzag relation, and where a pole of maximum strength is required they may 80 be arranged upon each side thereof, though for some purpose it will be sufficient to have them upon less than all the sides, as upon two opposite sides only, for example. They are also preferably disposed in a crossed relation as shown, throughout all or a considerable part of the length of the pole, which materially contributes to the strength of the 85 pole. Furthermore, there is preferably employed, a series of transverse strips 20, which are arranged at suitable distances apart upon all or some of the sides of the pole, preferably with their ends adjacent to 90 ends of the elements 15.

Whatever the relative disposition of the 95 members referred to may be in other respects, it is important that they be such that they may be electrically welded together at the places of contact, so as to provide an economically-produced skeleton structure of 100 strength adapted to the purpose for which the pole is designed.

Two forms, adapted for spot welding and ridge welding respectively, are shown in the 105 accompanying drawings. In the first of these, shown in Fig. 3, either or both members at the places of contact are formed with an appropriate number of protuberances, as 110 25, arranged therein at the place or places where it is to intersect, or be intersected by another member. These protuberances form projections from the bodies of the members,

- and through them the welding current is passed and by their use becomes effective to weld together the intersecting surfaces of the members, even though the latter be flat.
- 5 In the other of the forms referred to, the principle of contacting elements projecting from the surfaces of the intersecting members is retained, but said elements instead of being simple protuberances are ribs extending longitudinally of their respective members, or either one of the same and preferably continuous throughout the length thereof. This form is shown in Figs. 5, 6, 7, 8 and 9, the last named figure showing the appearance of the parts after the welding has been effected and the other figures showing the parts in assembled and non-assembled form, prior to the welding operation. It will be noted that the projections are flattened at the welded places, whether such projections be simple protuberances (see Fig. 4) or ribs (see Fig. 9).

The pole may be utilized to support an object which calls for one or more lateral supports therefrom. An example of this is illustrated in the pole shown for electrical conductors, as telegraph or telephone poles, having arms projecting laterally therefrom. In the illustrated form of the invention 30 these arms, designated 23, have flat faces and are welded in the manner already described, to the flat faces of the vertical members. Inclined braces 24 may be employed as supports for these arms, and these braces 35 should be welded, as described with reference to the other members, to the flat faces of the vertical members and arms. The arms are shown as arranged upon opposite sides of the poles, with their ends converging and 40 the insulators may be disposed therein in line with each other or in staggered relation, as preferred.

Attention is called to the fact that the relative disposition of the members as shown 45 in the drawings is such as to permit convenient access to all the intersecting portions by the electrodes or terminals employed in the welding operation, and to permit the pole to be supported by the table used in 50 welding and to be moved along said table as the welding progresses. Each longitudinal bar is arranged with its open side outward and in position to engage the edge of the table upon which the welding is done. Thus, 55 it will be noted upon reference to Fig. 1, that this side of the pole shows the flanged bars each arranged with the edge of one portion as α , presented outward and the face of its other portion, α' , presented toward the 60 inside of the pole: while viewed from the side seen in Fig. 2, the face of the first portion α is outward and the other portion α' extends toward the corresponding member at the opposite side of the pole. (See also 65 Figs. 3 and 5.) This particular arrange-

ment is essential to a convenient and economical welding of the parts together, for the reason that each bar presents a surface which may rest on the table and receive the lower terminals or electrodes, with nothing to obstruct the welding operation and the movement of the bar longitudinally on the table step by step as the welding progresses and all of the junctions are readily accessible to the terminals of the welding apparatus; 70 whereas if the members A were otherwise arranged, that is, if they were so disposed as to present their closed sides outward at the corners of the posts, instead of their open sides as herein shown, the junctions 75 would be practically inaccessible and the welding operation could not be rapidly proceeded with on the welding table and the welding operation would be produced at a cost which would be substantially prohibitive. 85

The base of the pole, if desired, may be provided with a plate or other suitable foundation element, as 30, and the top thereof similarly may be provided with a plate or other suitable cap-element 31. 90

From the foregoing the construction of my pole will be readily seen and it will be observed that I have provided one which while comparatively light and may be inexpensively produced, yet has the utmost 95 strength and durability. Being of skeleton structure it may be easily transported and will withstand wind stresses as well as all other strains and stresses to which it may be subjected. The parts being welded together become integral, and the weakening due to rivets is avoided, and the welding operation may be performed at less cost than that incident to riveting. It is practical to form the device either at the place 100 of use, or at a factory, and in the latter event it may be shipped at a comparatively 105 normal cost.

While the invention has been referred to as a "pole" and reference has been made to 110 poles used for telegraph, telephone, electric lighting and trolley wires, yet it is to be understood that the term "pole" is used in a generic sense in the present case and that it is intended to include therein devices more 115 or less analogous to poles though ordinarily given other names in view of particular uses to which they are put, among which may be mentioned, "masts" used on shipboard and elsewhere for various purposes, 120 "staffs" used for flags and other purposes, "columns" for supporting floors or other things in building and engineering arts, "towers" used for a variety of purposes in various arts, and in fact, a great many other 125 things having specific names which need not be referred to herein, but to which the applicability of the present invention will be readily suggested to those familiar with such things. Moreover, it may be used as 130

a beam for supporting floors or other elements of buildings or other structures, or it may be used horizontally or in other position, as well as vertically. In short, it is 5 my purpose to apply my present invention to various uses to which it is applicable, and these uses whether herein expressed or not are intended to be covered thereby.

Having now described the invention, what 10 I believe to be new and desire to secure by Letters Patent, is:

1. A metal device of the character described comprising a plurality of flanged longitudinally arranged elements of angular 15 cross-section, said elements being arranged in pairs, the included angle of each longitudinal element being outwardly disposed, connecting members welded to the outer faces of the longitudinal elements, the included angle faces of the longitudinal elements being left entirely unobstructed.

2. A metal device of the character described, comprising a plurality of flanged longitudinal elements of angular cross-section, 20 said elements being arranged in pairs, the included angle of each longitudinal element being outwardly disposed, the flanges

in pairs projecting in the same plane inwardly and outwardly from each other, and connecting members welded to the outer 30 faces of each longitudinal element, the included angle faces thereof being left entirely unobstructed.

3. A metal device of the character described comprising a plurality of flanged 35 longitudinal elements, the flanges thereof being disposed substantially at right angles to each other, said elements being arranged in pairs, the included angle of each longitudinal element being outwardly disposed and 40 flanges of each oppositely disposed pair projecting in the same plane and connecting members welded to the outer faces of the flanges of each longitudinal element, the included angle faces thereof being left entirely unobstructed. 45

In witness whereof I have hereunto set my hand at city of N. Y., county of New York, and State of New York, this 2nd day of April 1910.

MAURICE LACHMAN.

In presence of—

JOSEPH A. KEHOE,
LAURENCE T. LACHMAN.
